United States Patent Office.

CHARLES WALKER, OF CHESTER, VERMONT.

Letters Patent No. 77,339, dated April 28, 1868.

IMPROVED BED-BOTTOM.

The Schedule referred to in these Letters Patent and making part of the same.

TO ALL WHOM IT MAY CONCERN:

Be it known that I, CHARLES WALKER, of Chester, in the county of Windsor, and State of Vermont, have invented a new and useful Improvement in Spring-Bed Bottoms; and I do hereby declare that the following is a full, clear, and exact description thereof, which will enable others skilled in the art to make and use the same, reference being had to the accompanying drawings, forming part of this specification.

Figure 1 is a top or plan view of my improved spring-bed bottom.

Figure 2 is a vertical longitudinal section of the same, taken through the line *x x*, fig. 1.

Figure 3 is a vertical cross-section of the same, taken through the line *y y*, fig. 1.

Similar letters of reference indicate corresponding parts.

My invention has for its object to furnish a neat, simple, durable, convenient, and elastic bed-bottom, and one which can be easily and quickly put up or taken down; and it consists in the construction and combination of the various parts, as hereinafter more fully described.

A are the longitudinal spring-slats, which should be made light and elastic, and about twelve, more or less, of which should be used in a four-foot bedstead. The spring-slats *A* rest upon and are secured to the upper ends of coiled-wire springs *B*, the lower ends of which rest upon and are removably secured to the cross-slats *C*. The upper sides of the slats *C* are grooved or hollowed out longitudinally to receive the lower coil of each of the springs *B*, so as to hold them securely in place, and at the same time allow them to be easily removed when required.

D are spring cross-slats, of the same length and breadth as the cross-slats *C*, and the middle parts of which are secured to the middle parts of the cross-slats *C*, by screws or other convenient means; said spring-slats *D* being kept at a proper distance from the cross-slats *C* by the interposition of blocks, *E*, of suitable thickness. *F* are coiled-wire springs, placed between the ends of the cross-slats *C* and *D*, as shown in fig. 3.

The ends of the slats *D* rest upon slats or cleats attached to the inner side of the side rails of the bedstead, or in metallic loops attached to or hooked upon the upper edge of the said side rails of the bedstead.

In ordinary or light bedsteads, the double springs *D F* may be omitted, and the ends of the cross-slats *C* be supported directly from the side rails of the bedstead in the manner hereinbefore described.

In the case of very heavy beds, three sets of cross-slats and springs may be used; but, in ordinary cases, two sets will be sufficient.

G are cross-slats, which rest upon the ends of the spring-slats *A*, and which have downwardly-projecting pins *H* attached to them, which pass through holes or slots in the ends of the said slats *A*, so as to guide the said slots in their up-and-down movement, while at the same time allowing each slat *A* to move entirely independent of the others, as shown in fig. 2.

I claim as new, and desire to secure by Letters Patent—

The spring-bed bottom, constructed as described, and consisting of the transverse supports *C*, spring cross-slats *D*, blocks *E*, springs *B F*, slotted slats *A*, and loose cross-bars *G*, provided with pins *H*, all constructed, arranged, and operating substantially as and for the purposes specified.

The above specification of my invention signed by me, this 18th day of February, 1868.

CHARLES WALKER.
